BY

Charles E. Wiener
ATTORNEY,

UNITED STATES PATENT OFFICE.

CHARLES M. PROCTOR, OF DETROIT, MICHIGAN.

GONG.

1,237,384.

Specification of Letters Patent. Patented Aug. 21, 1917.

Application filed July 6, 1914. Serial No. 849,148.

To all whom it may concern:

Be it known that I, CHARLES M. PROCTOR, a citizen of the United States, residing at Detroit, county of Wayne, State of Michigan, have invented a certain new and useful Improvement in Gongs, and declare the following to be a full, clear, and exact description of the same, such as will enable others skilled in the art to which it pertains to make and use the same, reference being had to the accompanying drawings, which form a part of this specification.

This invention relates to gongs for electric bells and the objects and novel features of construction thereof are hereinafter more fully described and claimed and shown in the accompanying drawings in which—

Figure 1 is an elevation of an electric bell showing my improved gong.

Fig. 2 is a section of the gong taken on line $\alpha-\alpha$ of Fig. 1.

Similar characters refer to similar parts throughout the drawings and specification.

As with the usual electric bell, the gong is generally mounted on a base 1 of any approved type which also carries an electromagnet within a casing 2, and having the usual ball hammer 3 on the end of the armature adapted to strike the gong. In the manufacture of electric bells of the same size it is desirable that the gongs be productive of the same volume of sound but of divergent tone whereby several contiguous signal bells may be distinguished one from the other. The gong 4 here shown is substantially of the shape of a ball having a slot 5 upon one side thereof extending to the axis of the gong, and terminating upon both the upper and lower sides in an enlarged aperture 6, 6. To support the said gong, a post 7 is provided secured in any approved manner to the base 1 extending through one of the apertures 6 and preferably into an aperture in a lug 8 formed upon the interior of the bell and provided with an aperture in alinement with the said apertures 6, 6, into which an end of the post extends. A screw 9 is provided extending through the aperture in the lug 8 and into a threaded socket in the post.

A gong of the type shown should be struck near the slot or bifurcation 5 in order to produce the greatest resonance and by providing the interiorly projecting lug the gong may be mounted centrally on the portion of the base to which it is attached, providing a bell of neat appearance and of peculiar tone.

Having thus briefly described my invention, and its utility, what I claim and desire to secure by Letters Patent of the United States is—

1. A gong comprising a substantially ball shaped metal shell having a slot on one side terminating in enlarged apertures on opposite sides of the bell in axial alinement, and a lug upon the interior of the shell having an aperture in alinement with said apertures in the shell. 65

2. A gong for electric bells and the like 70 consisting of a metal shell having a slot upon one side thereof terminating in enlarged apertures centrally upon opposite sides of the bell, and a lug formed integrally with said shell having an aperture in axial 75 alinement with said apertures in the shell.

3. A gong for electric bells and the like 80 consisting of a substantially ball shaped metal shell having a slot upon one side thereof terminating in enlarged apertures 85 centrally upon opposite sides of the shell, a lug formed integrally therewith extending into the interior of the shell and having an aperture in alinement with said apertures in the shell, and a post for supporting said 85 gong extending into the shell through one of said apertures.

4. In a device of the character described, a substantially ball shaped gong having a slot in one side, and a lug for supporting the 90 gong extending from the opposite side of the interior thereof and integrally formed therewith.

In testimony whereof, I sign this specification in the presence of two witnesses.

CHARLES M. PROCTOR.

Witnesses:

SELENE McDONALD,
CHARLES E. WISNER.
